UNITED STATES PATENT OFFICE

161,696

LIQUID DISPENSER FOR WEED KILLER

Fred J. Lee, Pasadena, Calif.

Application December 5, 1949, Serial No. 6,426

Term of patent 14 years

(Cl. D52—2)

To all whom it may concern:

Be it known that I, Fred J. Lee, a citizen of the United States, residing at Pasadena, in the county of Los Angeles and State of California, have invented a new, original, and ornamental Design for a Liquid Dispenser for Weed Killer, of which the following is a specification, reference being had to the accompanying drawings, forming part thereof.

Fig. 1 is a perspective view of a liquid dispenser for weed killer showing my new design.

Fig. 2 is an enlarged view in side elevation with an intermediate portion of the dispenser broken away.

I claim:

The ornamental design for a liquid dispenser for weed killer, substantially as shown.

FRED J. LEE.
